SHEDDING MECHANISM FOR LOOMS

Application filed November 27, 1931. Serial No. 577,516.

This invention relates to looms and more particularly to a shedding mechanism including novel means controlling a multiplicity of harness frames.

5 Sheding mechanisms may be divided, generally, into three classes, namely, cam shedding mechanism, dobby or head motion shedding mechanism and jacquard shedding mechanism. Of these the first is ordinarily 55 used for simple work involving the use of not more than six or eight harness frames, the second is used for more complex work requiring up to possibly, twenty harness frames, and the third is used for the production 60 of intricate designs which would require the use of more harness frames than can conveniently be mounted on a loom.

It is the principal object of my invention to provide harness frame operating mechanism which shall be adaptable for use with any number of harness frames from two up to the capacity of the present dobby, and which shall be simple in construction and efficient in operation.

25 A further object of my invention is to provide a harness frame operating mechanism including a single pair of pivoted, oppositely reciprocating treadles connectible, under control of a pattern surface, with any of a plurality of harness cords, the points of connection with the various harness cords being at the proper distance from the fulcrum of the treadles to cause all of the harnesses to open the warps to substantially the same angle.

30 Other objects, not specifically enumerated, will become apparent as the description proceeds.

The preferred embodiment of my invention, herein disclosed, includes any desired 40 number of harness frames mounted, as usual, in substantially parallel planes and vertically reciprocated for controlling the position of the various warp threads. Each harness frame is connected, top and bottom, with harness cords running over a set of sheaves. At least one sheave in each set is provided 45 with a spring detent tending to hold the respective harness frame in raised or lowered position. The harness cords pass from the top of the frame, around the sheaves, down-

wardly past the end of the frame, around more sheaves and up to the bottom of the frame and, in the present instance, are contained entirely in the plane of the respective frame. A pair of treadles are pivoted, one 55 above the other, below the harness frames, on a vertical axis contained in the vertical plane which includes the fell of the cloth. These treadles extend rearwardly, one above and the other below the lowermost runs of 60 the harness cords. One treadle is reciprocated by a single cam. The second treadle is reciprocated from the first treadle, but in an opposite direction. Cooperating means on the treadles and cords are provided selectively connecting any or all of the cords for movement with either treadle, under control of a pattern surface. Thus, the single cam serves to raise or lower any or all of the harness frames in any desired sequence, under 65 control of the pattern surface.

Referring more particularly to the drawings:

Fig. 1 is a view in front elevation of a loom embodying my invention,

Fig. 2 is an end elevation, taken from the left of Fig. 1, and,

Fig. 3 is a sectional plan view with parts broken away or omitted to more clearly show the mechanism involved.

The frame work of the loom embodying my invention may consist of the usual loom sides 1 and 2 carrying arches 3 and 4 and connected by girts such as 5 and 6. Suitable harness frames 7 of the desired number are supported in substantially parallel vertical planes between the arches. The various mechanisms of which the loom is comprised are driven from a main shaft 8 and cam shaft 9 journalled in boxes on the loom sides, and since these mechanisms, with the exception of the shedding mechanism, may be of any usual construction and form no part of the present invention they need not be illustrated or described.

As above indicated, there may be any suitable number of harness frames, but only two, the extreme front and the extreme rear frames, are illustrated other than diagrammatically. The various frames are supported

and operated by duplicate sets of harness cords operating over suitable sheaves. Of these duplicate sets only one need be described in detail. Referring more particularly to Fig. 1, a cord, or strap, 10 is connected as by harness connector 11 with the top of the front harness frame 7. This cord passes over a sheave 12 rotatably mounted on a stud supported by the arches 3 and 4 and is fastened to a second sheave 13, similarly mounted. A second cord 14 connects the sheave 13 with the right hand end of the harness frame. A cord 15, likewise fast at one end to sheave 13, passes downwardly past the end of the harness frame, thence about a sheave 16 and across the loom beneath the frame, and thence about a sheave 17 and up to the bottom of the frame. Another cord 18 has one end fixed to the sheave 16 and the other end fixed to the bottom of the harness frame. It will thus be seen that the frame is mounted for movement independent of the movements of the other frames.

I prefer to provide means for releasably locking each frame in raised or lowered position. Such means, in the present instance, is comprised of a spring pressed plunger 19 guided in an adjustable block 20 supported by brackets 20' on the arches, and adapted to engage behind a projection 13' or 13'' on sheave 13, constituting, in effect, a spring detent.

A pair of treadles 21 and 22, directly below the harness frames, are pivoted on a vertical pin 23. This pin is positioned in the vertical plane containing the fell 24 of the cloth being woven (see Fig. 2). The treadles extend from the pivot pin rearwardly through the planes of the harness frames, on opposite sides of the lower runs of the harness cords 15, the treadle 21 extending above the cords and the treadle 22 extending below the same. The treadle 21 is provided, on its upper surface, with a roller 25 engaging in a cam groove 26 in a cam 27 fixed on cam shaft 9, whereby the treadle is reciprocated lengthwise of the adjacent cords 15 in a horizontal plane.

The rear end of treadle 21 engages a pin in the upper run of a chain 28 passing about idler sprockets 29. The treadle 22 engages a pin on the lower run of the chain 28, and, therefore, reciprocates oppositely to the direction of reciprocation of the treadle 21.

The cords 15 are each provided with a block 30, or other suitable form of latch member for engagement with cooperating members such as recessed blocks 31 provided on the contiguous faces of the treadles. Pivoted fingers 32 loosely engaging the cords control the engagement and disengagement of the latch members with the blocks on the treadles, there being one such finger for each cord. In the present instance each finger 32 is pivoted at one end on a pin 33 carried by a girt

5, and is provided at its other end with a recess loosely embracing the respective cord.

The fingers 32 are controlled by a suitable pattern surface, constituted in the present instance by a conventional pattern chain 34 operating over sprockets 35 and carrying rows of removable pins 36 directly engaging the fingers. The right hand sprockets 35 are feathered on a shaft 36' slidably and rotatably mounted in bearings on the loom frame. The rear end of this shaft 36' carries a collar 37 having a clutch face adapted to co-operate with a clutch face on a worm gear 38 loosely mounted on the shaft and driven through worm 39, shaft 40 and gearing 41 from the cam shaft 9. A coil spring 42 extending between one of the shaft bearings and a collar 43 fixed on the shaft 36' tends to hold the said clutch faces in engagement. However, by means of a hand wheel 44, the shaft 36' may be pushed rearwardly to disengage the clutch and then rotated to adjust the pattern surface, i. e. to "find the pick."

The operation is as follows:

Considering the front harness only, this harness is shown in Fig. 1 in its lowermost position, with latch 30 on the front cord 15 engaging block 31 on the lower treadle 22. Assuming that it is desired to leave the harness in this lowered position for one pick, a pin 36 will be provided on the pattern chain which will engage the front finger 32 and raise it just before the treadle 22 starts to move to the left, thus disengaging the latch 30 from the block 31. The treadle 22 will then move to the left and treadle 21 will move to the right without moving this front harness cord, the spring detent 19 on sheave 13 locking the harness frame in its lowered position. Since the cam shaft, as is usual, makes one complete revolution for each two picks, at the end of one pick it will have made one half revolution and the treadles will have changed positions. That is, treadle 21 will be to the right of pivot pin 23 and treadle 22 will be to the left thereof. If it is now desired to raise the front harness a pin 36 will be provided in the pattern chain which will raise the front finger 32 and thus raise the cord 15 until latch 30 is positioned in the recess in block 31 on the upper treadle 21 which treadle will then move to the left and by virtue of being connected to cord 15 will raise the harness frame against the action of the spring detent. The front harness frame may then be left locked in raised position for any desired number of picks and then lowered, by the proper positioning of pins in the pattern chain.

With the parts again in the position shown in Fig. 1 should it be desired to raise the front harness frame immediately instead of leaving it lowered during one pick as above, a pin will be omitted from the pattern chain, allowing latch 30 to remain in the recessed block while the treadle 22 moves to the left, after

which time the latch will be allowed to remain in the block or will be disengaged therefrom at the dictates of the pattern surface.

Since a separate row of pins 36 is provided 5 from each finger 32 and the harness frames are independently mounted it will readily be seen that, according to the pattern, any or all of the cords may be selectively connected for movement with either treadle in any desired 10 sequence.

It is noted that since the point of connection of each cord 15 with the treadles is in the plane of the respective harness frame and the pivot point of the treadles is in the vertical 15 plane containing the fell of the cloth each frame will be moved a distance which is directly proportional to the distance of the respective frame from the fell of the cloth. Thus all of the frames will open the shed to 20 exactly the same angle. This same result could be obtained, though not as conveniently, by other relationships of the parts, the essential feature being that the distance from the connection between the treadle and each cord 25 to the pivot point of the particular treadle be directly proportional to the distance from the respective harness frame to the fell of the cloth.

It is also noted that while I prefer to position the treadles and associated parts directly 30 underneath the harness frames and to pivot the treadles on a common axis they may, in certain instances, be positioned elsewhere and the treadles may be separately mounted, although the construction shown is much more 35 compact and susceptible of simplicity in design.

It is, therefore, to be understood that the embodiment of my invention herein disclosed 40 is for purposes of description only and not of limitation, and that numerous variations may be resorted to within the scope of the appended claims.

I claim:

45 1. A shedding mechanism for looms, comprising a plurality of harness frames, means including harness cords for raising and lowering each harness frame independently of the others, means for locking each frame in raised or lowered position, a pair of treadles positioned respectively above and below 50 lengths of said cords directly underneath the harness frames, means for reciprocating said treadles in opposite directions lengthwise of said cords and pattern controlled means for 55 selectively connecting any of said lengths of cords for movement with either of said treadles, to thereby move the respective harness frame from one locked position to the other.

60 2. A shedding mechanism for looms, comprising a plurality of harness frames, harness cords operatively associated with each frame for raising and lowering the same, means for locking each frame in raised or lowered 65 position, a pair of treadles positioned one

above the other directly underneath the frames, each treadle being pivoted at its front end on a vertical axis and extending rearwardly crosswise of said harness cords, a cam for reciprocating one of said treadles in a 70 horizontal plane, means connecting the second treadle with the first treadle for reciprocation in the opposite direction, and pattern controlled means for selectively connecting any of said cords for movement with either of said treadles to thereby move the respective harness frame from one locked position to the other.

3. A shedding mechanism for looms, comprising a plurality of harness frames, harness cords operatively associated with each frame for raising and lowering the same, a pair of treadles positioned respectively on opposite sides of said cords, a cam for reciprocating one of said treadles lengthwise of the cords, means connecting the second treadle with the first treadle for simultaneous reciprocation thereby in the opposite direction, and pattern controlled means for selectively connecting any of said cords for movement with either 85 treadle.

4. A shedding mechanism for looms, comprising a plurality of harness frames, harness cords operatively associated with each frame for raising and lowering the same, means for locking each frame in raised or lowered position, a pair of treadles positioned respectively on opposite sides of the cords, said treadles being pivoted adjacent their front ends and extending rearwardly crosswise of said cords, cam means for reciprocating said treadles in opposite directions lengthwise of the portions of said cords positioned therebetween, and pattern controlled means for selectively connecting any of said cords for movement 95 with either treadle.

5. A shedding mechanism for looms, comprising a plurality of harness frames, harness cords connected with the top and bottom of each frame for raising and lowering each frame independently of the others, sets of sheaves for guiding said cords in their movements, a spring detent for one sheave in each set tending to hold the respective harness frame in raised or lowered position, a pair of oppositely reciprocating treadles for moving the cords, and pattern controlled means for selectively connecting any of the cords with either treadle.

6. A shedding mechanism for looms, comprising a plurality of harness frames, each frame being supported and operated by a set of independent harness cords connected to the top and bottom of the respective frame and passing around sheaves contained in the plane of the frame, at least one sheave of each set being provided with a spring detent tending to hold the sheave stationary when the harness is in either raised or lowered position,

and cam means for operating said cords to thereby raise or lower the harnesses.

7. A shedding mechanism for looms, comprising a plurality of harness frames positioned in parallel planes, harness cords connected to move each harness frame independently of the others, a pair of oppositely reciprocating treadles each of which is pivoted to move about an axis, and means for selectively connecting any of the said cords with either treadle, at a distance from the said axis directly proportional to the distance of the respective frame from the fell of the cloth, to thereby produce a uniform shed opening.

8. A shedding mechanism for looms, comprising a plurality of harness frames positioned in parallel planes, harness cords connected to move each harness frame independently of the others, a pair of oppositely reciprocating treadles pivoted in the plane, parallel to the harnesses, containing the fell of the cloth being woven, said treadles extending rearwardly through the planes of the harness frames, and means for independently connecting the harness cords for each successive frame to the treadles, the connecting means for each frame being located in the plane of the respective frame, whereby the treadles will move each frame a distance which is directly proportional to its distance from the fell of the cloth, to thereby provide a uniform shed opening.

9. A shedding mechanism for looms, comprising harness frames positioned in adjacent vertical planes, means for individually locking said frames in raised or lowered position, a pair of oppositely reciprocating treadles pivoted in the vertical plane containing the fell of the cloth being woven and extending rearwardly therefrom, harness cords for moving the frames against the action of said locking means, and pattern controlled means for connecting any of said harness cords with either treadle at a point in the plane of the respective frame.

10. A shedding mechanism for looms, comprising a plurality of harness frames positioned in parallel vertical planes, harness cords connected with the top and bottom of each frame and extending around the end thereof in the plane of the respective frame, a pair of oppositely reciprocating treadles pivoted in the vertical plane containing the fell of the cloth being woven and extending rearwardly past the said harness cords, and means for selectively connecting any of said cords to the adjacent portion of either treadle in the plane of the respective harness frame.

11. A shedding mechanism for looms, comprising a plurality of harness frames, a pair of oppositely reciprocating treadles pivoted on a common axis, a plurality of harness operating cords extending laterally of said treadles therebetween, there being one such

cord for each harness frame, pivoted fingers for establishing an operative connection between any of the cords and either treadle, and means including a pattern surface for operating the fingers.

12. A shedding mechanism for looms, comprising harness frames, a pair of oppositely reciprocating treadles, harness operating cords extending laterally of said treadles therebetween, there being one such cord for each harness frame, recessed blocks on the contiguous faces of the treadles adjacent each cord, a latch member on each cord adapted to be positioned in the recess in the adjacent block on either treadle, and pattern means for selectively controlling the engagement of the latch members with the blocks.

13. A shedding mechanism for looms, comprising harness frames, means for individually locking said frames in raised or lowered position, a pair of oppositely reciprocating treadles, a plurality of harness operating cords extending laterally of the treadles therebetween, opposed recessed blocks on the contiguous faces of the treadles adjacent each cord, a latch member on each cord adapted to be positioned in the recess in the adjacent block on either treadle, pivoted fingers controlling the relation between the various latch members and blocks, and means including a pattern for operating said fingers.

14. A shedding mechanism for looms, comprising a plurality of harness frames, a pair of oppositely reciprocating treadles pivoted on a common axis, a plurality of harness operating cords extending laterally of said treadles therebetween, there being one such cord for each harness frame, pivoted fingers for establishing an operative connection between each cord and either treadle, means including a pattern surface for operating the fingers, and means including a clutch for driving said pattern.
